W. H. DE BUSK

RAIL ANCHOR

Filed Aug. 9, 1924

Patented Nov. 17, 1925.

1,562,303

UNITED STATES PATENT OFFICE.

WILLIAM H. DE BUSK, OF CHICAGO, ILLINOIS, ASSIGNOR TO THE P. & M. COMPANY, OF CHICAGO, ILLINOIS, A CORPORATION OF ILLINOIS.

RAIL ANCHOR.

Application filed August 9, 1924. Serial No. 731,061.

To all whom it may concern:

Be it known that I, WILLIAM H. DE BUSK, a citizen of the United States, residing at Chicago, in the county of Cook and State of Illinois, have invented certain new and useful Improvements in Rail Anchors, of which the following is a specification.

My invention relates to rail anchors of the type adapted to be applied to a railroad rail in position to abut against a cross-tie or other fixed portion of a track for holding the rail against movement longitudinally. It is the principal object of my invention to provide a new and improved form and arrangement of parts in an anchor of this type comprising a clip or jaw member adapted to be driven into gripping engagement with the flange of a rail from one side thereof and improved means for holding the clip from backing transversely from the flange.

It is another object of my invention to improve devices of this type in sundry details hereinafter pointed out. The preferred means by which I have accomplished my objects are illustrated in the drawing and are hereinafter specifically described. That which I believe to be new and desire to cover by this application is set forth in the claims.

In the drawing,—

Fig. 1 is a face view of my improved anchor in position on a rail shown in vertical section and partly broken away;

Fig. 2 is a top plan view of the anchor of Fig. 1;

Fig. 3 is a fragmentary view similar to a part of Fig. 1 but showing a changed position of the parts due to a slight difference in size of one or more of the parts;

Fig. 4 is a view similar to Fig. 1, but showing a modified form of clip;

Fig. 5 is another view similar to Fig. 1 showing another modified form of anchor; and

Fig. 6 is a face view of the blank from which the retaining device of the anchor of Fig. 5 is formed.

Referring to Figs. 1 and 2,—10 indicates a rail, supported by a cross-tie 11. Upon the flange of the rail 10 at the right in Fig. 1, there is a clip or gripping member 12, comprising an upper arm 13, a lower arm 14, and a depending lug or arm 15. This member 12 is preferably formed of high-grade steel in the form of a forging bent into

shape from a heavy bar, with its arms 13 and 14 separated by a smaller distance than that necessary for receiving into operative position the flange of the rail as illustrated in Fig. 1.

When it is desired to apply the clip 12, the clip is placed in position loosely upon the flange of a rail and is driven toward the left in Fig. 1, causing the clip to spread slightly from the condition shown in dotted lines to the condition shown in solid lines. Inasmuch as the clip is harder than the steel of the rail and is formed of a bar of a size to give it considerable strength, the end of the arm 13 is caused to bite into the upper face of the flange, producing a transversely-extending groove 16^a which assists in maintaining the clip in its initial applied position longitudinally of the rail. The clip 12 is preferably applied in close proximity to the cross-tie 11, so that the lug or arm 15, as well as the arm 14, is in contact with the face of the cross-tie, providing a very good bearing on the tie.

For holding the clip 12 in position on the flange so as to maintain its efficiency for preventing the rail from creeping, I have provided a retaining-member comprising a bar 16, having a jaw 17 formed integrally on one end, the jaw 17 being preferably so disposed with relation to the bar 16 as to fit snugly over the edge portion of the flange of the rail 10, as illustrated in Fig. 1. At its other end, the bar 16 is provided with an integrally formed arm 18 which is designed to be so positioned as to extend snugly along the outer face of the clip 12 in contact therewith, when the retaining member is applied as hereinafter described. Upon the free end of the arm 18, there is provided a second arm 19 adapted to extend inwardly along the face of the clip toward the web of the rail, the end of the arm 19 being turned to provide a lug 20 overlying the clip 12 for supporting the arm 18 positively in operative position with respect to the clip.

After the clip 12 has been applied to the rail, the jaw 17 of the retaining member is first hooked over the opposite edge of the flange, and the arm 19 is brought into close proximity to the clip 12. The arm 19 is forced toward the right in Fig. 1 against the resiliency of the metal into position to clear the clip 12, whereupon the

retaining member is swung toward the cross-tie 11 to bring the arm 19 into engagement with the outer face of the clip 12. The retaining member is then driven toward the tie until the arm 19 snaps downwardly along the face of the clip above the cross-tie into the position shown in Fig. 2, in which the member is held against withdrawal except by the application of some little force thereto, and in which the arm 18 of the member serves effectively for preventing the withdrawal of the clip 12 transversely from the rail.

In case the flange of the rail should be slightly wider than normal, or the retaining member is slightly short, within certain prescribed allowable limits, the jaw 17 can be spread slightly as indicated by dotted lines in Fig. 3, by a blow or blows thereon at the left in said Fig. 3 for enabling the retaining member to move slightly toward the right in Fig. 1 for causing the desired snug fit of the retaining device upon the rail and clip.

The construction shown in Fig. 4 is substantially the same as that shown in Fig. 1, except that a modified form of clip 21 is used, and the lug 20 is omitted. The clip 21 is made from a heavy piece of sheet metal cut out at one side for providing the spaced jaws as desired, the spacing being such that the clip cuts into the upper face of the rail as described in connection with the clip of Fig. 1. The lug 20 of the retaining member may be omitted in this construction by reason of the fact that the arm 18 is held by its contact with the vertically disposed outer face of the clip from slipping vertically out of normal position.

In the construction shown in Fig. 5, a third form of clip is illustrated. In this construction, the clip 22 is similar to the clip 12 except that the lug or arm 15 is omitted, the engagement of the clip with the cross-tie being effected by the lower arm only. In this construction, a retaining member formed of sheet metal is substituted for the bar structure of retaining member as above described. This retaining member is formed of substantially the same elements as those above described, comprising the transversely-extending body 23, the jaw 24, the arm 25 extending longitudinally of the rail, the arm 26 extending transversely of the rail, and the lug 27 resting on the upper face of the clip 22 for holding the member in position with respect to the clip. In applying the retaining device of this figure to a rail, the arm 26 is first hooked over the flange before applying the jaw 24.

So far as I am aware, I am the first in the art to provide a rail anchor comprising a clip adapted to be driven into operative gripping engagement with the flange of a rail adjacent to a cross-tie, and a retaining

member adapted to be hooked over the edge of the flange at the opposite side of the rail and then brought into snap engagement with the clip for holding the clip positively against backing transversely from the flange of the rail, and my claims are to be construed accordingly.

While I prefer to employ one of the forms of device as illustrated in the drawing, it will be understood that I do not wish to be restricted to the use of the specific forms shown, except as the same may be hereinafter specifically claimed, it being clear that changes may well be made in the details of the construction without departing from the spirit of my invention.

What I claim and desire to secure by Letters Patent is—

1. A rail anchor comprising a clip adapted to be driven into operative gripping engagement with the flange of a rail, and a retaining member adapted to be hooked over the edge of the flange at the opposite side of the rail and then to be brought into snap engagement with the clip for holding the clip against backing transversely from the flange.

2. A rail anchor comprising a clip adapted to be driven into operative gripping engagement with the flange of a rail, and a retaining member adapted to be hooked over the edge of the flange at the opposite side of the rail and then to be brought into snap engagement with one face of the clip for holding the member in snug engagement with another face of the clip so as to hold the clip from backing transversely from the flange.

3. A rail anchor comprising a clip adapted to be driven into operative gripping engagement with the flange of a rail, and a retaining member adapted to be hooked over the edge of the flange at the opposite side of the rail, such retaining member comprising two arms one of which is adapted to engage the outer face of the clip for holding the clip from backing transversely from the flange when the member is swung toward the clip, and the other of which arms is adapted to have snap engagement with another face of the clip for holding the member in operative position with respect to the clip.

4. A rail anchor comprising a clip adapted to be driven into operative gripping engagement with the flange of a rail, and a retaining member comprising a hook at one end adapted to engage the edge of the flange at the opposite side of the rail, an arm so positioned with respect to the hook as to be capable of being swung horizontally into substantially rigid snug engagement with the outer face of the clip, and means for holding the arm in operative engagement with the clip.

5. A rail anchor comprising a clip adapted to be driven into operative gripping engagement with the flange of a rail, and a retaining member comprising a hook at one end adapted to engage the edge of the flange at the opposite side of the rail, an arm so positioned with respect to the hook as to be capable of being swung horizontally into substantially rigid snug engagement with the outer face of the clip, and means carried by the arm adapted by engagement with the clip to hold the arm in operative position with respect to the outer face of the clip.
- 10 6. A rail anchor comprising a clip adapted to be driven into operative gripping engagement with the flange of a rail, and a retaining member comprising a hook at one end adapted to engage the edge of the flange at the opposite side of the rail, an arm so positioned with respect to the hook as to be capable of being swung horizontally into substantially rigid snug engagement with the outer face of the clip, and means having snap engagement with the clip for holding the arm in operative position with respect to the outer face of the clip.
- 15 7. A rail anchor comprising a clip adapted to be driven into operative gripping engagement with the flange of a rail, and a retaining member comprising a hook at one end adapted to engage the edge of the flange at the opposite side of the rail, an arm so positioned with respect to the hook as to be capable of being swung horizontally into substantially rigid snug engagement with the outer face of the clip, and a second arm carried by said first-named arm at substantially right angles thereto adapted to have snap engagement with the clip for holding said first-named arm in operative position with respect to the outer face of the clip.
- 20 8. A rail anchor comprising a clip adapted to be driven into operative gripping engagement with the flange of a rail, and a retaining member comprising a hook at one end adapted to engage the edge of the flange at the opposite side of the rail, an arm so positioned with respect to the hook as to be capable of being swung horizontally into substantially rigid snug engagement with the outer face of the clip, means for holding the arm from swinging horizontally out of operative engagement with the clip, and means for supporting the arm in position vertically with respect to the outer face of the clip.
- 25 9. A rail anchor comprising a clip adapted to be driven into operative gripping engagement with the flange of a rail, and a retaining member comprising a hook at one end adapted to engage the edge of the flange at the opposite side of the rail, an arm so positioned with respect to the hook as to be capable of being swung horizontally into substantially rigid snug engagement with the outer face of the clip, means for holding the arm from swinging horizontally out of operative engagement with the clip, and means adapted by engagement with the clip for supporting the arm in position vertically with respect to the outer face of the clip.
- 30 10. A rail anchor comprising a clip adapted to be driven into operative gripping engagement with the flange of a rail, and a retaining member comprising a hook at one end adapted to engage the edge of the flange at the opposite side of the rail, an arm so positioned with respect to the hook as to be capable of being swung horizontally into substantially rigid snug engagement with the outer face of the clip, means for holding the arm from swinging horizontally out of operative engagement with the clip, and means carried by the arm adapted by engagement with the top face of the clip to support the arm in position vertically with respect to the outer face of the clip.
- 35 11. A rail anchor comprising a clip adapted to be driven into operative gripping engagement with the flange at one side of a rail, and a retaining member comprising a hook at one end adapted to engage the edge of the flange at the opposite side of the rail, an arm so positioned with respect to the hook as to be capable of being swung horizontally into substantially rigid snug engagement with the outer face of the clip, a second arm carried by said first-named arm at substantially right angles thereto adapted to have snap engagement with the clip for holding the said first-named arm from swinging horizontally out of operative position with respect to the outer face of the clip, and a lug carried by said second arm adapted to engage with the top face of the clip to hold the first-named arm in position vertically with respect to the outer face of the clip.

WILLIAM H. DE BUSK.
